UNITED STATES PATENT OFFICE.

ABRAHAM TAMARIN, FRANK TAMARIN, AND MAX HENDLER, OF HUDSON, NEW YORK,
ASSIGNORS TO KOMFYTITE SPRING AND BED CORPORATION, OF HUDSON, NEW
YORK, A CORPORATION OF NEW YORK.

ADJUSTABLE BEDSTEAD.

1,394,512.

Specification of Letters Patent. Patented Oct. 18, 1921.

Application filed March 14, 1921. Serial No. 452,035.

To all whom it may concern:

Be it known that we, ABRAHAM TAMARIN, FRANK TAMARIN, and MAX HENDLER, citizens of the United States, residing at Hudson, in the county of Columbia and State of New York, have invented certain new and useful Improvements in Adjustable Bedsteads, of which the following is a specification.

10 This invention relates to adjustable bedsteads, and it comprises a bed having a head board and a foot board connected by side rails, the head board and foot board each being provided with a pair of end rails 15 and a transverse member arranged above the end rails, said transverse member comprising a pair of sections, a sleeve surrounding said sections and connecting them to each other and means for retaining the 20 ends of said sections within said sleeve, and said end rails each comprising a pair of sections adapted to be secured to the head board and foot board respectively, a locking member hinged to one section adjacent its 25 inner end, the other section being provided with an elongated slot, the inner end of said second section being adapted to be received within said locking member and a bolt or pin carried by said locking member and received in said slot.

In the present invention, we have provided a bedstead which may be adjusted laterally to vary the width of the bed. The bedstead is particularly suited for use in 35 connection with the adjustable bed spring described and claimed in our copending application Serial No. 448,773, filed March 1, 1921.

The bedstead comprises a foot board and 40 a head board, each of which is provided with a pair of legs arranged at the four corners of the bed, the legs at the head or the foot of the bed being connected at their upper ends by means of a transverse member. Suitable means are provided for adjusting the length of the transverse member when the bed is to be adjusted.

Below the transverse member, the legs are connected by means of an end rail arranged 50 in the same horizontal plane as the side rails of the bed. The end rail is preferably formed of channel shaped metal or other material, and made in two sections, the outer end of each section being secured to the bed

post. Adjacent the inner end of one of the 55 sections, a locking member is arranged, the locking member comprising a channel shaped piece of metal adapted to surround the inner ends of the two sections to maintain them in proper position. This member is hinged to one of the sections and is provided with an opening for the reception of a bolt which passes through the elongated slot in the other section to retain the end rail in adjusted position. 65

In the accompanying drawings, we have shown one embodiment of the invention. In this showing:

Figure 1 is a perspective view of the bed assembled, 70

Fig. 2 is an end elevation of a portion of a head board or foot board, parts being shown in section,

Fig. 3 is a detail perspective view of one of the bed posts showing the manner of securing a side rail thereto, and, 75

Fig. 4 is a transverse vertical sectional view on line 4—4 of Fig. 2.

Referring to the drawings, the reference numeral 1 designates the head board, and 2 the foot board of the bed. The head board and foot board are connected by means of side rails 3, in the usual manner. As shown, the side rails are formed of angle iron and are provided with an arcuate plate 4 at 85 each end. This plate is provided with a slot 5 adapted to receive a headed pin 6, carried by the bed post 7. It will be apparent that the side rails may be readily removed when the bed is to be taken down 90 by lifting them to remove the pin 6 from the slot 5.

The construction of the head board and foot board is the same, and a description of one will, therefore, suffice. As stated, 95 they are each provided with a pair of posts or legs 7, arranged at the corners of the bed and connected at their upper ends by means of transverse members 8. The transverse members consist of a pair of sections, each 100 of which is secured to and forms a continuation of a bed post. In the drawings, the transverse members have been shown of circular cross-section but any style or shape may be employed instead. The inner ends 105 of the transverse members are surrounded by a sleeve 9, the sleeve being provided with an opening adjacent each end. The trans-

verse members are provided with a plurality of threaded openings 10, for the reception of a bolt or screw 11, adapted to pass through the opening in the sleeve. It 5 will be apparent that when the screw 11 is passed through the sleeve into one of the openings 10, the transverse sections 8 will be secured to each other, through the medium of the sleeve, and the bed retained 10 as adjusted. By arranging the screw in different threaded openings, the width of the bed may be readily adjusted.

The bed posts are further connected by means of end rails 12, the ends rails being 15 preferably arranged in the same horizontal plane with the side rails and secured to the bed posts in any suitable manner. In the drawings, the end rails are shown rigidly attached to the posts, but they may be secured thereto by means of any suitable detachable fastening elements.

Each of the end rails comprises a pair of sections 13 and 14, preferably channel shaped in cross-section. A locking member 25 15 is hinged to one of the sections adjacent its inner end. As shown, the locking member is hinged to the section 14, as at 16. Adjacent the free end of the locking member, an opening is provided for the passage 30 of a bolt 17. This bolt is adapted to pass through an elongated slot in the other section 13, and to be retained in adjusted position by means of a nut 19. When in locked position, the locking member surrounds or 35 embraces the free end of the slotted section and rigidly secures it to the other section of the end rail, as shown in Fig. 4 of the drawings.

It will be noted from an inspection of Fig. 40 1 of the drawings, that the locking member is arranged to swing in a horizontal plane and is best arranged to swing outwardly from the bed to permit free operation thereof. The locking device is permanently secured to one section of the end rail by means 45 of the hinge 16, and is unlikely to become lost or misplaced when the bed is taken down.

It is to be understood that the form of our 50 invention herewith shown and described is to be taken as a preferred example of the

same, and that various changes in the shape, size, and arrangement of parts may be resorted to without departing from the spirit of the invention or the scope of the subjoined claims. 55

Having thus described our invention, we claim:

1. An adjustable bedstead comprising a head board and a foot board, side rails connecting said head board and foot board, said head board and foot board each comprising a pair of posts and a transverse member connecting said posts, means for adjusting said transverse member, an end rail connecting each pair of posts, each of said end rails comprising a pair of channel shaped sections, one of said sections being secured to each post, a locking member hinged to one section adjacent its inner end, and means 60 65 for retaining the other section within said locking member.

2. An adjustable bedstead comprising a head board and a foot board, side rails connecting said head board and foot board, said head board and foot board each comprising a pair of posts and a transverse member secured to the upper ends of the posts and connecting them, said transverse member being formed in two sections to permit adjustment, a sleeve surrounding the adjacent ends of said sections, means for retaining said ends within the sleeve, an end rail connecting each pair of posts, each of said end rails comprising a pair of channel shaped 70 75 members, one of which is secured to each post, a channel shaped locking member surrounding the inner ends of said sections, said locking member being hinged to one of said sections, the other section being provided 80 85 with an elongated slot, and a bolt carried by said locking member and adapted to be received in said slot.

In testimony whereof we affix our signatures in presence of two witnesses.

ABRAHAM TAMARIN.
